[57] CLAIM

The ornamental design for a solar powered marking light, as shown and described.

DESCRIPTION

FIG. 1 is a top, front, right side perspective view of a solar powered marking light showing my new design; FIG. 2 is a top plan view thereof on an enlarged scale; FIG. 3 is a fragmentary front elevational view thereof on an enlarged scale, the ground stake being fragmentarily shown for convenience of illustration; FIG. 4 is a left side elevational view thereof on an enlarged scale, the right side being a mirror image; FIG. 5 is a bottom plan view thereof on an enlarged scale; and FIG. 6 is a rear elevational view thereof on an enlarged scale. The ground stake is shown in broken lines for illustrative purposes only.
